UNITED STATES PATENT OFFICE.

MICHAEL E. CONNELLY, OF CUMBERLAND, MARYLAND.

TOILET.

987,112.

Specification of Letters Patent. Patented Mar. 21, 1911.

Application filed February 1, 1910. Serial No. 541,251.

To all whom it may concern:

Be it known that I, MICHAEL E. CONNELLY, a citizen of the United States, residing at Cumberland, in the county of Allegany and State of Maryland, have invented 5 certain new and useful Improvements in Toilets, of which the following is a specification.

My invention relates to water-closets, and 10 has for one of its objects the provision of a device of the above character which is capable of discharging its contents in a manner which is least objectionable.

A further object of my invention is to 15 provide a device of the above character embodying means whereby the same may be readily and securely attached to its support.

A further object of my invention is to 20 vide a novel form of seat to be used in connection with the water-closet.

My invention consists in the arrangement 25 and combination of parts to be hereinafter described.

25 In the accompanying drawings forming a part of this specification and in which like numerals are used to designate like parts throughout the same, Figure 1 is a side view of my device. Fig. 2 is a plan view of the 30 same with the seat removed. Fig. 3 is a plan view of a cap employed upon my device. Fig. 4 is a section taken on line 4—4 of Fig. 1. Fig. 5 is a detail section of one of the pins employed to support the seat 35 shown in Fig. 1.

In the drawings illustrating a preferred 40 embodiment of my invention, 1 designates a bowl or body portion of the water-closet, and this bowl tapering downwardly terminates in a cylindrical discharge chute 2. The discharge chute 2 is disposed within a suitable opening 3 formed upon a support 4. This support 4 may be the floor to an engine cab. Upon the upper and lower sides of the 45 floor-support 4 are arranged ring-shaped plates 5, which contain the discharge chute 2 and are fixedly secured thereto by means of solder or the like. The plates 5 are also fixedly secured to the floor-support 4 by any 50 suitable means.

The upper end of the bowl 1 is closed by 55 means of a cap 8, which is hinged to a fixed section 9, as at 10. The lower end of the discharge chute 2 is normally closed by means of a cap 12; which is hinged thereto,

as at 13. The cap 12 is provided at its periphery with an annular flange 14, within which the lower end of the discharge chute 2 snugly fits. The cap 12 is further provided with a plurality of small openings 15, 60 and said cap 12 is held in its normal seated position by means of a retractile coil spring 16, which is disposed within a housing 17, and connected to said cap 12 as at 18, and to the chute 2 as at 20. The purpose of the 65 housing 17 is to prevent the spring 16 from coming in contact with the contents of the bowl 1. Water under suitable pressure is conducted within the bowl 1 by means of a supply pipe 26, the free end of which is disposed within the bowl 1, as at 27. The supply pipe 26 is provided outside of the bowl 1 with a cut-off valve 28.

In order that my water-closet may be used in place of a stool, as for instance if 75 the same were arranged within an engine cab, I provide a removable seat 26, upon which is arranged a cushion 27. The seat 26' carries upon its lower side a plurality of fixed tubes 28', which are in turn provided with longitudinal slots 29. Within the tubes 28 are slidably mounted shafts 30, which carry pins 31 fixed thereto and disposed within the slots 29. Each of the shafts has its lower free end enlarged as at 32, and 80 around the shaft 30 and tube 28 is arranged a compressible coil spring 33, which tends to limit the longitudinal movement of said shaft 30. The shafts 30 are arranged upon the lid 8 as illustrated in Fig. 1, whereby the 85 seat 26' is spring supported. To prevent the displacement of the seat 26', said seat is provided with a hinge-leaf 34, which has its free end bent or looped at 35; for detachable engagement with a bracket 36, which is 90 fixedly secured upon the upper portion of the bowl 1.

The discharge chute 2 may be externally 95 screw-threaded as at 45 for the connection with a conveyer-pipe (not shown) for conducting the contents of the bowl 1, to a desired place.

In the use of my water-closet, the seat is first removed and the lid 8 raised, after the operator has answered a call of nature, the 105 lid 8 is closed and the cut-off valve is opened to allow water to flow into the bowl 1. This water will dissolve the foul matter within said bowl, which will accordingly pass through the perforated cap 12. By thus 110

dissolving the foul matter it is disposed of in a least disagreeable way. If sufficient water pressure is allowed to enter the bowl 1, the cap 12 will be unseated and the contents of the bowl 1 discharged through the chute 2 without passing through the apertures 15. It is preferred however, to force the contents of the bowl 1, through the perforated cap 12. If it is desired a pipe may be connected to the chute 2 and the contents of bowl 1 delivered to a desired location.

Having fully described my invention, what I claim is:

1. In a device of the character described, 15 a bowl tapering in one direction to form a stationary discharge chute, a lid hinged to said stationary chute to normally close the same, a spring disposed normally entirely within said chute and having its ends secured to said chute and lid, and a housing 20

for said spring disposed within said stationary chute and partially closing the same.

2. In a device of the character described, 25 a bowl tapering in one direction to form a stationary discharge chute, a lid provided with a plurality of perforations, hinged to said stationary chute to normally close the same, a spring disposed normally entirely within said chute and having its ends secured to said chute and lid, a housing for 30 said spring disposed within said stationary chute and partially closing the same, and a cover for the upper end of said bowl.

In testimony whereof I affix my signature in presence of two witnesses.

MICHAEL E. CONNELLY.

Witnesses:

FRANCIS S. DEEKENS,
CARL F. SCHMUTZ.
